CORNER LOCK FOR WINDOW SCREEN FRAMES

John J. Steinhauer, 2910 Humboldt St.,
Los Angeles, Calif. 90031

Filed Feb. 9, 1973, Ser. No. 331,242

Term of patent 14 years

Int. Cl. D8—08

U.S. Cl. D8—233

FIG.1

FIG.2

FIG.3

FIG.4

FIG.5

FIG.6

FIG. 1 is a perspective view from the front and to one side of a corner lock for window screen frames showing my new design;

FIG. 2 is a perspective view from the rear and to one side of said corner lock;

FIG. 3 is a front elevational view of said corner lock;

FIG. 4 is a rear elevational view of said corner lock;

FIG. 5 is a side elevational view of said corner lock; and

FIG. 6 is a side elevational view of the opposite side of said corner lock shown in FIG. 5.

I claim:

The ornamental design for a corner lock for window screen frames, substantially as shown and described.
